UNITED STATES PATENT OFFICE.

NILS FREDERICK AMBURSEN, OF NEWTON HIGHLANDS, MASSACHUSETTS, ASSIGNOR
TO THE UNI-FORM COMPANY, OF BOSTON, MASSACHUSETTS, A CORPORATION OF
MASSACHUSETTS.

APPARATUS FOR CONSTRUCTING CONCRETE FLOORS.

1,278,286.

Specification of Letters Patent. Patented Sept. 10, 1918.

Application filed December 13, 1917. Serial No. 206,939.

To all whom it may concern:

Be it known that I, NILS FREDERICK AMBURSEN, a citizen of the United States, and a resident of Newton Highlands, in the 5 county of Middlesex and State of Massachusetts, have invented a new and useful Improvement in Apparatus for Constructing Concrete Floors, of which the following is a specification.

10 The present invention which is an improvement on the apparatus for constructing concrete floors shown in my United States Letters Patent No. 1,216,644 dated February 22, 1917, has for its general object 15 the improvement and simplification of the clamps or spreaders used for securing the arch plates or floor forms to their channels or supports.

In said apparatus the clamps are grooved 20 to receive the reinforcing rods and the latter are secured to the clamps by means not integral therewith, such, for example, as wires which are twisted around the rods and clamps. Heretofore in apparatus of this 25 general type it has been customary to use "chairs" resting on the bottoms of the beam boxes for supporting the reinforcing rods, and sometimes hangers are used for suspending said rods in said boxes.

30 By means of the present invention, however, I provide means integral with the clamp for spacing or centering the reinforcing rods and securing them to the clamp, thereby accomplishing by means of a single 35 piece of apparatus a result which heretofore has required a plurality of devices, and in this way I am enabled to effect a considerable saving in time, labor and material. To this end, my invention in its preferred form 40 comprises a clamp having a body portion and a pair of prongs integral therewith and extending upwardly therefrom, said prongs being constructed and arranged to be bent over a reinforcing rod placed between the 45 same; but it will be understood that my invention is not limited to a clamp and has utility where it is desired to space reinforce-

ing rods and hold the same in fixed position while the concrete is being poured.

My invention will be explained by reference to the accompanying drawings in which—

Figure 1 is a side view of my improved clamp. Fig. 2 it a plan view. Fig. 3 is an end view. Fig. 4 is a transverse section of 55 a portion of a concrete floor constructed by means of my improved apparatus, the forms and their support member being shown in position. Fig. 5 is a plan view showing a portion of the mold before the concrete has been 60 poured. Figs. 6 and 7 are plan views of modified forms of my improved clamp. Figs. 8, 9 and 10 are diagrams which illustrate the action of the prongs in centering the reinforcing rods. Fig. 11 is a side view 65 of the bolt which I prefer to use with my clamp.

In the particular drawings selected for more fully disclosing my invention, 1 represents 70 a light channel iron having flanges 1', 1', the web of which is apertured at suitable intervals for receiving bolts 2 which pass freely through the same and are threaded into the holes 2' in the center of the clamps 3.

The clamps as shown consist of a body portion which preferably is upwardly bowed so as to raise the rods 4 supported thereby farther from the upper surface of the web of the channel, and still permit the ends of the clamp to engage the floor forms at points closer to said web, than if said clamp were straight, and to form a toggle, whereby the lower edges of said forms are more securely clamped against the flanges of the channel 80 85 than if the wedging action between the ends of a straight clamp and the inclined sides of the flanges were relied upon.

In the present instance the means integral with the body portion of the clamp for spacing the rods and securing them thereto consist of two pairs of prongs 5, 6, and 5', 6' stamped out of said body portion in the direction of its length and projecting up-

wardly from the opposite sides thereof, as shown in Fig. 2, said pairs being arranged on either side of the transverse axis of the clamp and constructed and arranged to be bent over a reinforcing rod resting on and extending across said body portion.

7, 7 represent metallic arch plates such as described in said Letters Patent or other suitable floor forms which span the spaces 10 between pairs of adjacent channels, having their lower edges resting on the webs of the channels and held in engagement with the flanges by the clamps as shown in Fig. 4. After the arch plates have been clamped in 15 position the reinforcing rods 4 are placed in the spaces between the pairs of prongs and the latter are then bent down over the rods to secure the same in position as shown in Figs. 4 and 5, each prong preferably being 20 long enough to extend over the center of a rod.

In assembling the floor mold I prefer to insert the bolts 2 through the webs of the channels and then thread them loosely into 25 the clamps before the channels are placed on the false-work. The channels are then placed upon their supports, the clamps turned in the direction of the channels and the arch plates placed in position, where- 30 upon the clamps are turned transversely of the channels and the bolts tightened by means of a screw driver which takes into the kerf 2' with which the threaded end of the bolt is provided. In this way all the 35 work of assembling can be done by men working overhead.

As will be obvious a single prong on either side of the transverse axis of the clamp may be used, the workman in such 40 case holding the reinforcing rod against such prong with his foot while hammering the prong over the rod.

I prefer however to use a pair of prongs, one pair on either side of the transverse axis 45 of the clamp because thereby the rods will automatically be centered. Figs. 8, 9 and 10 show how this is done. A rod dropped into the space between a pair of prongs may roll over against the side of one of them as 50 shown in Fig. 8. The prong 5 is then hammered down and drives the rod against the prong 6 as shown in Fig. 9, but when the prong 6 is forced against the rod, the latter will be moved over toward the left as shown 55 in Fig. 10 and will assume a position substantially in the center of the space between the prongs.

It will also be obvious that the prongs 60 may be stamped out of the center of the body portion as shown at 8, 9, 8', 9', in Fig. 6 and that they need not be formed on the opposite sides thereof. Fig. 7 shows a fur- 65 ther modification in which the prongs 10,

11, 10', 11', are stamped out of portions of the body of the clamp between the center 65 and the sides.

Various other modifications may be made in the several forms of clamp herein particularly described without departing from the principle of my invention. 70

It will be obvious that by means of the present invention considerable time and labor may be saved in erecting the forms and that various other elements heretofore considered essential may be eliminated. 75

Having thus described illustrative embodiments of my invention without, how- 80 ever, limiting the same thereto, what I claim and desire to secure by Letters Patent is:—

1. In an apparatus for constructing con- 85 crete floors, a clamping member comprising an upwardly-bowed body portion.

2. In an apparatus for constructing con- 90 crete floors, a channel, floor-forms having their lower edges against the flanges of said channel, a clamping member arranged to hold said edges of said forms against said flanges, and a bolt passing through the web of said channel and having threaded en- 95 gagement with said clamping member, the end of said bolt being provided with a trans- 100 verse kerf.

3. In an apparatus for constructing con- 95 crete floors, a channel, floor-forms having their lower edges against the flanges of said channel, and a clamping member arranged to hold said edges of said forms against said flanges, said clamping member having means integral therewith for securing rein- 100 forcing rods thereto.

4. An apparatus for constructing concrete 105 floors comprising a concrete-form support- member having upstanding edges, floor- forms having their lower edges against said upstanding edges of said support-member, and a clamping member arranged to hold said edges of said forms against said up- 110 standing edges of said support-member, said clamping member having means integral therewith for securing reinforcing rods thereto.

5. An apparatus for constructing concrete 115 floors comprising a concrete-form support- member having upstanding edges, floor- forms having their lower edges against said up- 120 standing edges of said support-member, and a clamping member arranged to hold said edges of said forms against said up- standing edges of said support-member, said clamping member comprising a body por- 125 tion and a pair of prongs projecting up- wardly therefrom, said prongs being spaced apart to receive a reinforcing rod between them.

6. An apparatus for constructing concrete 125 floors comprising a body portion and two

pairs of prongs integral therewith and projecting upwardly therefrom, said pairs of prongs being arranged on either side of the transverse axis of said body portion and 5 the respective members of each pair being arranged on opposite sides of the longitudinal axis thereof, one member of each pair being spaced lengthwise of said body portion from the other member thereof to receive a reinforcing rod resting on and ex- 10 tending across said body portion, said prongs being constructed and arranged to be bent over and immovably secure a reinforcing rod of any diameter equal to or less than the space between said prongs. 15

In testimony whereof, I have hereunto subscribed my name this 10th day of December, 1917.

NILS FREDERICK AMBURSEN.
